UNITED STATES PATENT OFFICE

2,599,877

LEATHER PUNCH

Roland G. Sweet, Pleasanton, Calif., assignor to
Alfred Roberts, Concord, Calif.

Application June 13, 1947, Serial No. 754,502

2 Claims. (Cl. 164—119)

1

This invention relates to an improved punch for forming a row of holes in leather to be hand laced and more particularly to a punch which is so constructed that the holes formed thereby will have their longitudinal axes disposed at an oblique angle to the axis of the row of the openings to accurately conform to the natural angle at which leather should be laced, thereby improving the appearance of the work after the lacing has been accomplished and producing a stronger construction by eliminating the gap ordinarily left, by conventional punches in the lace holes after lacing.

Still another object of the invention is to provide a punch the use of which will effect a substantial saving in the length of the lace required for a particular job and which will enable more rapid and better hand lacing, thus effecting economy in labor and material.

Still a further object of the invention is to provide a punch capable of use on thicker pieces of leather, such as cowhide and heavy tooling steer, usually employed in the making of ladies' handbags and purses, and which punch can be more readily withdrawn from the leather after the punching operation has been accomplished.

Still a further object of the invention is to provide a punch which will accomplish a finer and neater slit when used on thin leather.

Various other objects and advantages of the invention will hereinafter become more fully apparent from the following description of the drawing, illustrating a preferred embodiment thereof, and wherein:

Figure 1 is a perspective view of a punch constructed in accordance with the invention;

Figure 2 is an end view in elevation thereof looking toward the pronged or cutting end of the punch;

Figure 3 is an enlarged fragmentary plan view of a portion of the punch including one of the punching prongs;

Figure 4 is a cross sectional view through a prong taken substantially along a plane as indicated by the line 4—4 of Figure 3;

Figure 5 is an edge view in elevation showing the punch in operation, and

Figure 6 is a plan view of a partially laced piece of leather and showing the arrangement of the openings formed by the punch.

Referring more specifically to the drawing, the improved punch in its entirety is designated generally 1 and includes an elongated, relatively wide bar 8 which may be formed of any suitable material such as tool steel and which is notched and

beveled at one end thereof to form a series of transversely spaced, corresponding prongs or punching blades 9, each of which is provided with outwardly converging sides 10 which merge at their outer ends to form a cutting edge 11 and sides or faces 12 which are beveled slightly to converge toward the cutting edge 11, as best seen in Figure 5. The sides 10 of each of the prongs 9 are each disposed at an oblique angle to the plane 10 of the bar 8 and to the planes of the faces 12, as best seen in Figure 2.

The remainder of the bar 8 constitutes the handle or shank portion of the punch 1 and said punch, when in an operative position, is adapted 15 to be disposed substantially upright or perpendicular to a work piece to be engaged thereby, as seen in Figure 5, said work piece 13 constituting a piece of leather, as seen in Figure 6, in which a row of lace openings is to be formed. To form 20 the lace openings, the plane of the punch 11 is disposed parallel to and adjacent an edge of the piece of leather to be laced and the punch is driven downwardly by any suitable impact means for forming a row of openings 14 disposed parallel to said edge to be laced at any desired distance therefrom, and with the openings 14 spaced at intervals equal to the intervals between the prongs 9, by means of which said openings 14 are formed, by portions of the prongs 9 passing therethrough. This operation is repeated as many times as required to provide any desired number of openings 14.

As clearly illustrated in Figure 6, the openings 14 are individually disposed with their longitudinal axes oblique to the partially laced edge of the leather piece 13, so that when said edge is laced, as partially indicated at 15, the individual lacings extending along the sides of the leather piece 13 will be disposed approximately at right angles to the longitudinal axes of the openings 14 so that the portions of the lacings passing therethrough will substantially fill said openings 14 to provide a stronger and neater construction and to accomplish a saving in the length of lacing required for a given job due to the fact that there is no twisting of the lacing adjacent the openings 14.

Obviously, the punch 1 may be made of any desired width and to include any number of prongs 9, and various other modifications and changes are likewise contemplated and may obviously be resorted to, without departing from the spirit or scope of the invention as herein- 55 after defined by the appended claims.

I claim as my invention:

1. A leather punch of the character described consisting of an elongated flat bar provided with a series of transversely spaced notches in one end thereof forming a plurality of punching prongs at said bar end, said prongs being disposed in transversely spaced relationship relatively to said end of the bar and in transverse alignment, each of said prongs having outwardly converging sides forming a cutting edge at the outer end of the bar, each of said sides being disposed at an oblique angle relatively to the plane of the bar, the planes of said prongs and the planes of the cutting edges thereof all being disposed parallel to one another and at oblique angles to the plane of the bar, each of the prongs having two faces forming extensions of opposite sides of the bar.

2. A leather punch as in claim 1, and wherein the two faces of each prong are tapered toward the outer end of said prong and beveled slightly from the inner end to the outer end of the prong.

ROLAND G. SWEET.
